UNITED STATES PATENT OFFICE

117,838

DESIGN FOR A PADLOCK

Solomon Wise, Cleveland, Ohio

Application March 7, 1939, Serial No. 83,394

Term of patent 14 years

To all whom it may concern:

Be it known that I, Solomon Wise, a citizen of the United States and having as my post office address, 2730 Grand Avenue, in the city of Cleveland, county of Cuyahoga and State of Ohio, have invented a new, original, and ornamental Design for Padlocks, of which the following is a specification, reference being had to the accompanying drawing, forming part thereof.

Fig. 1 is a front elevational view of a padlock, showing my new design;

Fig. 2 is a rear elevational view of the padlock of Fig. 1;

Fig. 3 is a bottom plan view of the padlock of Fig. 1;

Fig. 4 is a top plan view of the padlock of Fig. 1, with a shackle element thereof in unlocked position;

Fig. 5 is an end elevational view of the padlock of Fig. 1, taken from the left-hand-side thereof;

Fig. 6 is an end elevational view of the padlock of Fig. 1, taken from the right-hand-side thereof.

I claim:

The ornamental design for a padlock, substantially as shown.

SOLOMON WISE.
